UNITED STATES PATENT OFFICE

HARRY D. FERTEL, OF NEW YORK, N. Y.

DESIGN FOR A COAT

Application filed September 20, 1929. Serial No. 32,812. Term of patent 14 years.

To all whom it may concern:

Be it known that I, HARRY D. FERTEL, a citizen of the United States, residing at New York, in the county of New York and State of New York, have invented a new, original, and ornamental Design for a Coat, of which the following is a specification, reference being had to the accompanying drawing, forming part thereof.

I claim:

The ornamental design for a coat, as shown.

HARRY D. FERTEL.
